Primary Examiner—Terry A. Wallace*Assistant Examiner*—Richelle Shelton*Attorney, Agent, or Firm*—Pennie & Edmonds[57] **CLAIM**

The ornamental design for a basket for holding container, as shown and described.

DESCRIPTION

FIG. 1 is a perspective view of a basket for holding container showing my new design;
 FIG. 2 is a rear elevation view thereof;
 FIG. 3 is a right side elevation view thereof;
 FIG. 4 is a left side elevation view thereof;
 FIG. 5 is a top plan view thereof;
 FIG. 6 is a front elevation view thereof;
 FIG. 7 is a bottom plan view thereof;
 FIG. 8 is a perspective view of a second embodiment of FIG. 1;
 FIG. 9 is a rear elevation view thereof;
 FIG. 10 is a right side elevation view thereof;
 FIG. 11 is a left side elevation view thereof;
 FIG. 12 is a top plan view thereof;
 FIG. 13 is a front elevation view thereof;
 FIG. 14 is a bottom plan view thereof;
 FIG. 15 is a perspective view of a third embodiment of FIG. 1;
 FIG. 16 is a rear elevation view thereof;
 FIG. 17 is a right side elevation view thereof;
 FIG. 18 is a left side elevation view thereof;
 FIG. 19 is a top plan view thereof;
 FIG. 20 is a front elevation view thereof;
 FIG. 21 is a bottom plan view thereof;
 FIG. 22 is a perspective view of a fourth embodiment of FIG. 1;
 FIG. 23 is a rear elevation view thereof;
 FIG. 24 is a right side elevation view thereof;
 FIG. 25 is a left side elevation view thereof;
 FIG. 26 is a top plan view thereof;
 FIG. 27 is a front elevation view thereof; and,
 FIG. 28 is a bottom plan view thereof.

The broken lines showing the environmental structure in all the views of a basket for holding container are for illustrative purposes only and form no part of the claimed design.
